DIVERTER FOR A SHOWER OR THE LIKE

Rene Mornard, St. Lambert, Quebec, Canada

Application May 23, 1957, Serial No. 46,306

Term of patent 14 years

(Cl. D91—3)

FIG.1

FIG.2

FIG.3

Figure 1 is a top plan view of a diverter for a shower or the like showing my new design;

Figure 2 is a side elevational view thereof; and

Figure 3 is a front elevational view thereof.

The dominant features of my design reside in the portions shown in full lines.

I claim:

The ornamental design for a diverter for a shower or the like, as shown and described.
